UNITED STATES PATENT OFFICE.

JOHN L. PREO, OF NEW YORK, N. Y.

SCORE-BOARD.

1,167,715.

Specification of Letters Patent.

Patented Jan. 11, 1916.

Application filed March 13, 1914. Serial No. 824,468.

To all whom it may concern:

Be it known that I, JOHN L. PREO, a citizen of the United States, and a resident of New York, borough of Brooklyn, county of 5 Kings, and State of New York, have invented a certain new and useful Improvement in Score-Boards, of which the following is a full, clear, and exact specification.

This invention relates to a class of devices 10 adapted to be employed for displaying the results of athletic games, and the like.

My invention has for its object primarily to provide a score board designed to be utilized for permitting the results of a series of 15 sporting events, especially baseball games and the like, to be displayed thereon in a manner whereby the score of the games played during a given period may be shown in their regular order, and wherein is employed a supporting board having on one face thereof a schedule divided into a number of parallel spaced vertical columns on each of which are designated the names of 20 the contesting clubs matched to play games on given days, and in the board between the columns are a number of pairs of spaced slits whereby the parts of the board therebetween may be guided in spaced relation to the face thereof which is opposite to the schedule so 25 as to provide vertically disposed pockets as well as serving as retaining members, or sections.

Another object of the invention is to provide one or a plurality of flexible scores slides, 30 or strips, one of which is removably inserted in each of the pockets between its retaining members and the adjacent marginal edges of the board; and still another object of the invention is to provide each score strip with 35 notched ends, or locking parts adapted to be engaged by the retaining members in a manner to hold the score strips against accidental displacement in the board.

A further object of the invention is to 40 provide a score board which is susceptible of being made of card board, or other cheap material so as to be sold at a very reasonable price.

With these and other objects in view, the 45 invention will be hereinafter more particularly described with reference to the accompanying drawing which forms a part of this specification, and will then be pointed out in the claims at the end of the description.

50 In the drawing, Figure 1 is a front elevation of one form of score board embodying

my invention. Fig. 2 is a section taken on the line II—II of Fig. 1, with the score strips removed therefrom. Fig. 3 is an elevation of one of the removable score strips 60 employed in the device, and Fig. 4 is a plan of an auxiliary removable slide adapted to be used in conjunction with the score board.

The device, or score board has a supporting board 10 which may be of any desired 65 shape and size, and this supporting board is preferably made of card board, or other material of a like class whereby the device may be manufactured to be sold at a very reasonable price. On one face of the score 70 board 10 is a schedule 11 which is printed, or otherwise inscribed thereon, and this schedule is of a size so that it occupies only a portion of the score board proper, in order to permit the space around the schedule to 75 be used for displaying advertising matter, or items of current news as occasion requires. The schedule 11 is divided into a number of parallel spaced columns, as 12, on each of which are designated the names of the contesting clubs, as shown at 13^b, that are matched to play games on given days, and while I show in the drawing the adaptability of the device for displaying the scores of 80 baseball games, it will be understood that 85 instead thereof other athletic events may be displayed thereon. In the board between the columns 12 of the schedule are a number of pairs of parallelly coursing slits, as 13 and 13^a, for reception of interchangeable 90 flexible score slides, or strips 16.

The flexible slidable score strips 16 are preferably alike in formation, and each strip is slightly longer as well as somewhat wider than the pockets of the supporting 95 board so that the marginal edges of each strip when inserted in one of the pockets will overlap the adjacent edges of the board at its pockets. In order to hold the score strips against accidental displacement in the 100 pockets 15 one or both of the upper and lower ends of each strip may be notched to provide locking parts, as 17 and 17^a. On one or both faces of the strips 16 is printed or otherwise inscribed a schedule 18 which 105 corresponds to the tabulations of the schedule 11 of the supporting board 10, and on the schedule 18 are displayed the score, as 19, made by each club in one or more games played during a number of days. After the 110 score on the strip has been suitably marked, the attendant slips its longitudinal edges

into the respective slits 13, 13^a of the pair of slits in the proper column, which is readily performed by flexing both the said strip and the part 14, so that the upper and 5 lower edges of the latter engage the cutouts 17, 17^a—Fig. 3—and the projecting lugs 17^b, 17^c extend beyond the length of the slits as indicated by the dotted lines in Fig. 1. Thus fixed in position, the strip 16 is 10 held non-movable both vertically and laterally and against bulging out longitudinally, which when the board is displayed out of doors would subject the strip to be blown out of its seat by a forceful gust of 15 wind.

If desired part of the lower portion of the supporting board 10 may be provided with two parallel vertically disposed spaced slits, as 20 and 21, in which is removably 20 inserted a slidable flexible strip 22 of card board or other like material. The strip 22 is somewhat wider than the length of the slits 20 and 21, and the upper and lower edges of this strip are notched, at 23 and 25 23^a. The notches 23 and 23^a are slightly wider than the section of the supporting board between the slits 20 and 21 so that when the strip 22 is inserted through the slits after the ends of the board have been 30 suitably bent the portion of the board therebetween may be guided into the notches 23 and 23^a for holding it against accidental displacement to the board, and on the strip 22 may be displayed any suitable item of news, 35 or other matter if desired.

In the foregoing description, I have embodied the preferred form of my invention, but I do not wish to be understood as limiting myself thereto, as I am aware that 40 modifications may be made therein without departing from the principle, or sacrificing any of the advantages of this invention, therefore I reserve to myself the right to make such changes as fairly fall within the 45 scope of the appended claims.

Having thus described my invention, I claim as new and desire to secure by Letters Patent:—

1. A device of the character described, 50 comprising a supporting board having a number of spaced vertical columns, a plurality of vertically disposed flexible retaining members provided on the board, one of

the members being arranged between each of two adjacent columns, and said members being in spaced relation to the board to provide vertically disposed pockets in the board, and a plurality of flexible strips, each being removably disposed in one of the pockets so that one of the faces of each strip 55 will be displayed in one of the spaces between the columns of the supporting board, substantially as described and for the purpose specified.

2. A device of the character described, 60 comprising a supporting board having a number of spaced vertical columns, a plurality of vertically disposed flexible retaining members provided on the board, one of the members being arranged between each 70 of two adjacent columns, and said members being in spaced relation to the body of the board to provide vertically disposed pockets in the board, and a plurality of flexible strips, each being removably disposed in one 75 of the pockets so that one of the faces of each strip will be displayed in one of the spaces between the columns of the supporting board, and the ends of each strip having 80 notches in which are seated the parts of the supporting board at the ends of the pockets in which the strip is disposed, substantially as described and for the purpose specified.

3. In a device of the character described, 85 a flexible supporting board having spaced vertically disposed columns and an integral section therebetween, formed by a pair of vertically disposed slits in the board, and the flexible section being disposed in spaced relation to the body of the board to form a 90 pocket, and a flexible strip disposed in the pocket so that one of its faces is displayed in the space between the columns, and the ends of the strip having notches in which are seated the parts of the supporting board 95 at the ends of the slits for removably locking the strip to the supporting board, substantially as set forth and for the purpose specified.

This specification signed and witnessed 100 this twelfth day of March, A. D. 1914.

JOHN L. PREO.
